DESIGN FOR A TEXTILE FABRIC OR SIMILAR ARTICLE

Robert Frick, New York, N. Y.

Application June 16, 1939, Serial No. 85,527

Term of patent 3½ years

To all whom it may concern:

Be it known that I, Robert Frick, a citizen of the United States, residing in New York city, in the county of New York and State of New York, have invented a new, original, and ornamental Design for a Textile Fabric or Similar Article, of which the following is a specification, reference being had to the accompanying drawing, forming part thereof.

Fig. 1 is a plan view of a textile fabric or similar article showing my design, and

Fig. 2 is the reverse side thereof.

My design is characterized by the appearance of vertical groups of alternately spaced stripes of diverse texture and color, interspersed by parallel rows of horizontal stripes.

I claim:

The ornamental design for a textile fabric or similar article, substantially as shown and described.

ROBERT FRICK.
